UNITED STATES PATENT OFFICE.

RAYMOND ROURKE, OF ROCK GLEN, NEW YORK.

POCKET ATTACHMENT.

1,018,929.

Specification of Letters Patent.

Patented Feb. 27, 1912.

Application filed March 16, 1911. Serial No. 614,918.

To all whom it may concern:

Be it known that I, RAYMOND ROURKE, a citizen of the United States, residing at Rock Glen, in the county of Wyoming and 5 State of New York, have invented certain new and useful Improvements in Pocket Attachments, of which the following is a specification.

This invention primarily aims to provide 10 a clasp or an attachment for pockets whereby certain articles, such as pens, pencils, rulers, and the like, may be carried with perfect safety. Although this attachment may be worn on any apparel provided with 15 pockets, it is especially adapted for wearers of overalls, such as carpenters, where there is a possibility of loss of a pencil or ruler.

To guide or permit the easy insertion of a 20 pencil or ruler into the pocket, a novel means is provided which is carried by the attachment and engages the edge of the pocket centrally.

With the above and other objects in view, this invention consists in the combination, 25 construction, and arrangement of parts, all as hereinafter more fully described, claimed, and illustrated in the accompanying drawings, wherein—

Figure 1 is an elevation illustrating the 30 attachment carried by a pocket; Fig. 2 is a vertical sectional view taken on line 2—2 of Fig. 1; Fig. 3 is a transverse section taken on line 3—3 of Fig. 1; Fig. 4 is a detail perspective of the attachment embodying the 35 present invention; Fig. 5 is a perspective of a modified form of attachment.

Throughout the following detail description and on the several figures of the drawings, similar parts are referred to by like 40 reference characters.

In carrying out the present invention, a single strip of spring material is provided having the terminals or arms 1 parallel to each other while the portion intermediate 45 the arms 1 is bent upon the latter, as at 2, to form a guard or clasp 3 adapted to retain articles in the pocket. The arms 1 are stitched in the pocket, as disclosed in Figs. 1 and 3 and, as the several portions of the 50 attachment lie in the same plane, it will be obvious that the insertion of a pencil or ruler into the pocket will force the guard portion 3 outwardly against the tendency of the spring material, the latter exerting

sufficient friction upon the article to prevent the dislodgment thereof. 55

It is oftentimes difficult to insert the ruler or pencil within the pocket and, to remedy the same, a guide member 4 is pivotally mounted on the guard or transverse bar 3, 60 the latter being bent upwardly, as at 5, to form a suitable bearing for said pivoted member. The free terminal of the pivotal guide member 4 is bent upon itself to form a clasp or hook 7 adapted to bind over the 65 edge of the pocket as shown in Fig. 2 and thereby aid in retaining the attachment to the pocket as well as serving the purpose of a guide. By having the guide member 4 pivoted in the bent portion 5 of the guard 3, 70 said guide member is prevented from any lateral movement when the attachment is carried by the pocket. Were this not the case, the guard member would be at liberty to have a transverse movement which would 75 render said guide member useless since the same would easily be displaced. Furthermore, the pivotal mounting of the guide member permits a free yielding movement of the edge of the pocket and does not in any 80 way interfere with the easy insertion of any article into the pocket.

In Fig. 5 is illustrated a modified construction of the pocket attachment having the parallel arms 1' bent at 2' and forming 85 the guard 3', the latter lying in a different plane from that in which the parallel arms lie. The guard 3' is bent downwardly at 5' at which point is pivotally mounted the guide 4', which has its free terminal bent to 90 form a hook 7' adapted to clasp over the edge of the pocket. If it is desired, the hook 7' may be provided with teeth 6 to more surely prevent dislodgment of said 95 guide member. It is intended that the shapes of the several parts of the attachment may be varied within the scope of the claims, as will be obvious. Were it not for the guide member 4, any attempt to insert the rule into the pocket would cause the latter to bag just opposite the guard and it would therefore be necessary for the wearer of the guard to use his free hand to pull the guard away from the pocket. In the present invention, the guard will be forced away 100 from the pocket by the ruler or the like bearing outwardly upon the guide member when inserting said ruler. Furthermore,

the guide serves to open the pocket when a ruler is inserted and made to contact with the pocket-edge end of the guide.

Having thus fully described my invention, what is claimed as new is:—

1. A guard attachment for pockets comprising a transverse bar and means for securing said bar to overlie the outer wall of a pocket, and a guide member mounted on said transverse bar and engaging the upper edge of said wall, said guide member being adapted to aid in inserting an article into the pocket when the article is made to contact with the pocket-edge of said guide.
2. An attachment for pockets comprising a downwardly bent guard provided with a central crimped portion, a pair of parallel

arms formed on said guard and adapted to be inserted within a pocket, and a guide member pivotally secured to said guard at 20 said crimped portion, the free terminal of said guide member being bent to form a hook adapted to engage the edge of the pocket, said guide being adapted to aid in opening the pocket when an article is inserted and made to contact with said free terminal, as herein specified.

In testimony whereof I affix my signature in presence of two witnesses.

RAYMOND ROURKE.
